UNITED STATES PATENT OFFICE.

WILLIAM W. WALLACE, OF KNOXVILLE, TENNESSEE.

DUMPING-CAR.

SPECIFICATION forming part of Letters Patent No. 781,577, dated January 31, 1905.

Application filed December 12, 1904. Serial No. 236,466.

To all whom it may concern:

Be it known that I, WILLIAM W. WALLACE, a citizen of the United States, residing at Knoxville, in the county of Knox and State of Tennessee, have invented a new and useful Improvement in Dumping-Cars, of which the following is a specification, reference being had to the accompanying drawings.

My improvement relates particularly to dumping-cars comprising a body or box adapted to tilt laterally and having a door at its sides to be opened for the lateral discharge of the load.

The object of the invention is to produce improved mechanism for automatically shifting either of the doors into the open and closed positions.

A specific object is to provide for the movement of the door at the lower side of the tilted car-body to such distance from the car-body as will make ample room for the discharge of the load.

Another specific object is to provide for the automatic locking of the doors when closed.

In the accompanying drawings, Figure 1 is an end elevation of the upper portion of a car embodying my improvement, the right-hand portion being broken away. Fig. 2 is a side elevation of the structure shown in Fig. 1. Fig. 3 is a section on the line 3 3 of Fig. 1 looking to the right. Fig. 4 is a section on the line 4 4 of Fig. 1 looking to the right. Fig. 5 is a section on the line 5 5 of Fig. 1 looking to the right.

Referring to said drawings, A is a portion of the underframing of the car. At each end said underframing comprises an inverted-V shape member A'.

B is the body or box of the car. Said body is pivoted to said members A' on the axis 1 by means of ears 2, extending downward from the bottom of said body and secured to said member by bolts 3. Said body comprises the relatively stationary floor 4, the relatively stationary end walls 5, and the shiftable walls or doors 6. As the doors are preferably duplicates, only one need be described in detail, and as the mechanism at one end of the door is a duplicate of the mechanism at the other end of

the door the mechanism at only one end need be described in detail. Obviously the car may have only one door. Each door is supported by a hinged bar 7 and a hinged bar 8, hinged to the end of the door. Said door may be joined to said bars in any suitable manner. The drawings show ears 9 applied to the door adjacent to each of said bars and having journals 10 extending through said bars and cotter-pins 11 extending through said journals outside of said bars. This construction permits the door to partake of the movements of said bars 7 and 8. The bars 7 have their inner ends hinged to the car-body to permit movement parallel to the end wall of the car. For convenience and economy in construction I have shown in the drawings the ends of said bars overlapping and secured by a single bolt 12, said bolt passing loosely through said bars and preferably immovably through the adjacent end wall 5, the filling-block 13, interposed between said bars and said wall, and the upright brace-plate 14, extending over said bars outside of the latter.

Between the ends of each bar 7 a lifting member 15 is hinged by its upper end to the bar 7 by a horizontal bolt 16 and extends thence downward to a point immediately above the outer side of the underframing, where it is hinged to one end of an approximately horizontal link 17 by a horizontal bolt 18, the opposite end of said link extending over one side of the V-shape member A' and hinged thereto by a horizontal bolt 19. From the foregoing description it will be seen that said lifting member 15 controls the adjacent horizontal bar 17. When the car-body is in the horizontal position, the lower end of each lifting member 15 is a little above the adjacent horizontal plate A² of the underframing, and each such member is suspended from the adjacent bar 7, and the latter is supported by the hinge-bolt 12 and the adjacent door, the latter resting by its weight upon the floor of the car-body. When the car-body is tilted laterally, as shown by Fig. 1 of the drawings, the lower end of the lifting member 15 at the side of the car-body which is lowered soon rests upon the adjacent plate A² and is there-

by prevented from descending further. Hence as the side of the car descends further the adjacent bar 7 and the adjacent door 6 are held against further downward movement, excepting the limited downward movement due to the lowering of the upper end of said lifting member by the outward turning of said bar upon its lower end in response to the lateral or outward movement of said bar 7 by the lateral movement of the hinge-bolt 12, to which the inner end of said bar is secured.

Chains C, attached to each side of the car-body and the adjacent portions of the underframing of the car, serve to hold the car-body in the horizontal position. When the load is to be dumped, the chains opposite the discharge side of the car are released.

The structure thus far described is old.

The lower portion of the door has heretofore been controlled by a bar which did not permit the opening of the door a distance sufficient for the ready discharge of loads. By means of my bar 8 I effect a further outward movement of the lower portion of the door when the car-body is tilted, and said bar also serves to firmly lock the door when the car-body is in the horizontal position.

A horizontal reinforcing-plate 20 extends across the middle portion of the outer face of each end wall approximately in line with the outer ends of the bars 8. A guide-plate 21 is immovably secured to the outer face of the brace-plate 14 and extends a short distance beyond each edge of said brace-plate. The upper edge of said guide-plate is flared outward away from said brace-plate. The inner end of each bar 8 extends between the reinforcing-plate 20 and the adjacent end of the adjacent guide-plate 21. To each inner end of each bar 8 is hinged one end of a link 22 by a horizontal bolt 22^a, and the opposite end of each such link is hinged on a horizontal stud or bolt 23, extending outward from the plate 20 at a point between and a little above the two hinges of the adjacent bar 8. To impart to said bolt or stud 23 greater stability, a bracket-plate 24 is applied by its lower edge to the reinforcing-plate 20 and extended thence outward and upward and around the outer end of said bolt. To clear said bolt, the inner half of said bar 8 is curved upward, as clearly shown in Fig. 1. The guide-plate 21 and the reinforcing-plate 20 are separated sufficiently by the intervening brace-plate 14 to make room for the overlapping ends of the bar 8 and the link 22 and the bolt 22^a, by which said bar and link are joined to each other. The upper edge of said guide-plate is flared outward in order that said bar 8 and said link may the more readily enter between said plates 20 and 21 when the car-door is being closed. In the closed position, (indicated by solid lines in Fig. 1,) as already described, the outer hinge of the link 22 is above the two hinges

of the bar 8. Hence any outward pressure exerted against the lower portion of the door is resisted by said link 22, for the strain imparted to said link through the bar 8 will be on a line below the bolt 23, and there will be no tendency to lift the outer end of said link. On the contrary, the tendency is to draw the outer end of said link downward. Thus the lower portion of the door is very securely locked so long as the car-body is in the horizontal position; but when that side of the car-body is lowered, as already described, the adjacent lifting member 15 relatively lifts the adjacent bar 7, whereby the adjacent door is lifted, and the outer end of the adjacent bar 8 is lifted until the line cutting the hinges of said bar is above the outer hinge of the link 22; or it might be said that that side of the car-body descends more rapidly than the adjacent bar 8, whereby the bolt 23, to which the outer end of the adjacent link 22 is hinged, is carried downward below the line cutting the hinges of the bar 8. Thus the inner end of said link 22 may rise and permit the bar 8 to move bodily outward. Such outward movement may continue until the inner hinge of the bar 8 is between the outer hinge of said bar and the bolt 23 and in line with said outer hinge and said bolt; but in order to facilitate the closing of the door when the car-body is again brought into the horizontal position, it is preferable to limit the downward movement of the inner end of said bar 8, so that the hinge which joins said bar and said link will remain a little above a line cutting the outer hinge of the bar 8 and the bolt 23, whereby said link is free to turn upward and inward on the bolt 23. To thus limit the downward movement of the bar 8, any suitable stop may be applied to the car in such position as to engage said bar when it has descended to the desired limit. For this purpose the drawings show a stop-block 25 applied to the lifting member 15 in proper position to engage the lower portion of the bar 8 when the latter has descended as far as is desired, and the drawings show the relative arrangement and proportions of the parts, such as to also bring said stop-block into engagement with the lower edge of the bar 8 when the car-body is in the horizontal position and the inner end of said bar has descended far enough to bring a line cutting the two hinges of said bar below the axis of the bolt 23.

The lifting member 15 is preferably composed of two bars 15^a, extending along opposite sides of the stop-block 25, and the bars 7 and 8 and the link 17.

The bar 8 and the link 22 may be operated manually for the outward movement of the lower edge of the door when the car-body is in the horizontal position.

I claim as my invention—

1. The combination with an underframing

and a tiltable car-body mounted upon said underframing and comprising a movable side door, of bars, 7, hinged by their outer ends to the upper portion of the door and by their inner ends to the car-body, bars, 8, hinged to the lower portion of each end of the door and joined to the car by a laterally-shiftable connection, whereby they are made laterally shiftable with reference to said bars, 7, and thereby adapted to permit the lower edge of the door to move away from the car-body farther than the upper edge of the door moves, substantially as described.

2. The combination with an underframing and a tiltable car-body mounted upon said underframing and comprising a movable side door, of bars, 7, hinged by their outer ends to the upper portion of the door and by their inner ends to the car-body, bars, 8, hinged to the lower portion of each end of the door and joined to the car by a laterally-shiftable connection, whereby they are made laterally shiftable with reference to said bars, 7, and thereby adapted to permit the lower edge of the door to move away from the car-body farther than the upper edge of the door moves, and mechanism for lifting said bar, 7, substantially as described.

3. The combination with an underframing and a tiltable car-body mounted upon said underframing and comprising a movable side door, of bars, 7, hinged by their outer ends to the upper portion of the door and by their inner ends to the car-body, bars, 8, hinged to the lower portion of each end of the door, and links, 22, each hinged by one end to the inner end of one of said bars and by its other end to the car-body, substantially as described.

4. The combination with an underframing and a tiltable car-body mounted upon said underframing and comprising a movable side door, of bars, 7, hinged by their outer ends to the upper portion of the door and by their inner ends to the car-body, bars, 8, hinged to the lower portion of each end of the door, and links, 22, each hinged by one end to the inner end of one of said bars and by its other end to the car-body, and mechanism for lifting said bar, 7, substantially as described.

5. The combination with an underframing and a tiltable car-body mounted upon said underframing and comprising a movable side door, of bars, 7, hinged by their outer ends to the upper portion of the door and by their inner ends to the car-body, bars, 8, hinged to the lower portion of each end of the door and joined to the car by a laterally-shiftable connection, whereby they are made laterally shiftable with reference to said bars, 7, and thereby adapted to permit the lower edge of the door to move away from the car-body farther than

the upper edge of the door moves, and mechanism for lifting said bars, 7, and guiding the bars, 8, substantially as described.

6. The combination with an underframing and a tiltable car-body mounted upon said underframing and comprising a movable side door, of bars, 7, hinged by their outer ends to the upper portion of the door and by their inner ends to the car-body, bars, 8, hinged to the lower portion of each end of the door, and links, 22, each hinged by one end to the inner end of one of said bars and by its other end to the car-body, and mechanism for lifting said bars, 7, and guiding the bars, 8, substantially as described.

7. The combination with an underframing and a tiltable car-body mounted upon said underframing and comprising a movable side door, of bars, 7, hinged by their outer ends to the upper portion of the door and by their inner ends to the car-body, bars, 8, hinged to the lower portion of each end of the door and joined to the car by a laterally-shiftable connection, whereby they are made laterally shiftable with reference to said bars, 7, and thereby adapted to permit the lower edge of the door to move away from the car-body farther than the upper edge of the door moves, and mechanism for guiding the bars, 8, substantially as described.

8. The combination with an underframing and a tiltable car-body mounted upon said underframing and comprising a movable side door, of bars, 7, hinged by their outer ends to the upper portion of the door and by their inner ends to the car-body, bars, 8, hinged to the lower portion of each end of the door, and links, 22, each hinged by one end to the inner end of one of said bars and by its other end to the car-body, and mechanism for guiding the bars, 8, substantially as described.

9. The combination with an underframing and a tiltable car-body mounted upon said underframing and comprising a movable side door, of bars, 7, hinged by their outer ends to the upper portion of the door and by their inner ends to the car-body, bars, 8, hinged to the lower portion of each end of the door, and links, 22, each hinged by one end to the inner end of one of said bars and by its other end to the car-body, and mechanism for limiting the downward movement of said bars, 8, substantially as described.

In testimony whereof I have signed my name, in presence of two witnesses, this 9th day of December, 1904.

WILLIAM W. WALLACE.
